UNITED STATES PATENT OFFICE.

CHARLES E. HORNE, OF MILLBURY, AND CHARLES D. PARKER, OF WORCESTER,
MASSACHUSETTS.

APPARATUS FOR SURFACING ROADS AND THE LIKE.

1,048,165.

Specification of Letters Patent.

Patented Dec. 24, 1912.

Application filed March 6, 1911. Serial No. 612,608.

To all whom it may concern:

Be it known that we, CHARLES E. HORNE and CHARLES D. PARKER, citizens of the United States, respectively residing at Millbury and Worcester, both in the county of Worcester and State of Massachusetts, have invented a new and useful Apparatus for Surfacing Roads and the Like, of which the following is a specification.

10 This invention relates to an apparatus for treating the surface of roads, pavements and the like.

The principal objects of the invention are to provide a practicable and convenient combination of parts for the purpose to take the place of the ordinary crude construction used for that purpose; also to provide such a combination with means whereby power from the road roller can be taken directly to 20 a motor or engine carried along with the road roller but detachable therefrom; to drive a pump for forcing the surfacing material from a tank in a uniform manner through the nozzles under pressure; to provide means whereby the molten material from the tank will be heated by exhausted steam from the engine throughout practically all its travel from the tank to the nozzles and even while it is in the nozzles; to 30 provide a series of practical and efficient connections between the tank and pump and between the pump and nozzles for accomplishing the above mentioned results; to provide a construction in which an operator can 35 take up a position so as to control the discharge of road surfacing material through the nozzles and also control the position of the nozzles relative to the path over which the road roller travels; to provide a convenient mechanism by which the nozzles can be arranged in a plurality of sets and the liquid turned on to all of them at once or to only one or more of the sets, as desired; to 40 provide an improved way of connecting the tank with the road roller so arranged that when disconnecting the parts, the drippings of molten material will be deposited directly on the ground and to provide improvements in details of construction as will appear 45 hereinafter.

Reference is to be had to the accompanying drawings in which—

Figure 1 is a side elevation of a road surfacing apparatus constructed in accordance with this invention. Fig. 2 is a similar view 55 on enlarged scale with parts in section of the rear vehicle shown in Fig. 1 and the elements mounted thereon. Fig. 3 is a rear end elevation of the same. Fig. 4 is a horizontal sectional view of the line 4—4 of Fig. 3. 60 Fig. 5 is a plan of the connection between the tank vehicle and rear vehicle, and Fig. 6 is a side elevation of the same with parts broken away.

Several devices have been invented, and 65 some of them have been constructed, for the purpose of treating the surfaces of roads with asphaltum oil, bitumen, and similar road surfacing material, but they have generally been of a comparatively crude and 70 incomplete construction so that, the material has not been uniformly distributed and much of the time of the gang of men employed has been wasted, and the full efficiency could not be obtained from the road 75 roller and other parts of the apparatus. For the purpose of overcoming these defects and securing the objects which have been mentioned, this invention is made.

The invention is illustrated in a form in 80 which a road roller A of any usual construction and therefore not illustrated in full herein but shown as steam operated, is connected up by means of a removable tongue 10 with a vehicle B on which is located a 85 tank C for containing the oil or other road surfacing material. Connected to the rear of the vehicle B by means which will be described hereinafter is a third vehicle D shown as having only two wheels. On this 90 is mounted a rotary pump E for taking the material from the tank C and discharging it through nozzles F. This pump is shown as operated by a steam engine G receiving steam from the road roller. By providing a 95 series of elements of this character it will be seen that each device is complete in itself so that a tank that has been emptied can be removed and returned to a place for being filled while another one is substituted so that 100

the work goes right along without material interruption. Thus each element can be used with maximum of efficiency. For the purpose of practically connecting them up so as to accomplish these results, the tank vehicle is provided with a steam pipe 11 connected by a flexible hose 12 with a live steam pipe 13 from the boiler of the road roller. Consequently the pipe 11 is provided with live steam. It in its turn is connected by a flexible hose 14 with a steam pipe 15 supported by the vehicle D. This steam pipe leads to the steam inlet of the cylinder 16 of the engine G, the piston rod 17 of which is connected by a crank shaft 19, pinion 20, and gear 21 with the rotary pump E. A fly wheel 23 is shown on the shaft 19. The details of the pump need not be described as any form of rotary pump can be employed, but it will be understood that the rotary pump is used for the purpose of securing a uniform instead of a pulsating pressure and consequently, a uniform flow of the liquid surfacing material as will appear hereinafter.

The vehicle D is drawn behind the tank vehicle partly by means of the pipe connections which connect the interior of the tank with the intake of the pump. For this purpose the tank is provided with an outlet pipe 25 having a valve 26 for controlling it and that is connected by pipe fittings 27 with a flexible hose 28 adapted to be supported when not in use, by a hook 29 on the vehicle D. The hose is connected with a pipe 30 which leads into the intake 31 of the pump.

The vehicle D is provided with a fixed forward projection 35 on which is pivoted at 36 a movable tongue 37. This tongue is connected by a pin 38 with a bracket 39 fixed to the straight branch of a Y forming part of the pipe fittings 27. Consequently the vehicle is drawn along with the tank vehicle. In order to control the direction of motion of the vehicle D so as to keep it properly in position, a curved rack 40 is mounted on the rear end of the tongue 37 and is caused to mesh with a pinion 41 on a rod 42 at the top of which is a hand wheel 43 within reach of an operator standing on the platform of the truck D. Also in reach of the foot of the operator is a pawl 44 normally forced by a spring 45 to engage the teeth of the pinion 41. Simply by manipulating this pawl by means of the foot the operator can control the direction of motion of the vehicle D by the hand-wheel 43 and when he gets it properly into line with the road roller he can leave the pawl alone and it will hold the tongue in position.

The material from the pump passes through a pipe 50 into a horizontal outer chamber 51. This chamber is provided with a plurality of outlets 52—52—52 each one fitting into a section 53 of the distributing

pipe. The three sections of this pipe shown in the drawings are connected with each other by couplings 54 having valves 54^a therein so that they can be connected with each other or separated, as desired. When separated each one of the pipes 52 is controlled by a separate valve 55. Each of these valves has an arm 56 for operating it, these arms being connected with an operating lever 57 by means of a series of links 58, one for each arm. One of these links is shown as connected directly with the lever 57 by means of a hook 59 which engages a pin 60 on a projection on the lever. Another one is connected by a similar link 61 with another pin 62 on the lever. The lever is provided with an opposite projection having a pin 63 with which a link 64 connected with a third lever 56 is connected in the same way. Obviously this lever 57 can be connected up with either one, two or three of the valve operating arms so as to supply the liquid material from the distributing chamber 51 to the desired number of sections of the pipe 53. The latter is provided with a plurality of openings 68. In each of these openings is the nozzle F of any desired kind.

In order to provide a safety device for preventing any damage in case the nozzles get stopped up, a by-pass 75 is provided from the pipe 50 back to the pipe 30 and in this is located a relief valve 76 which, under ordinary pressure, will remain closed but will open if the pressure becomes excessive and allow a circulation of the liquid down into the pipe 30.

In order to provide for keeping the molten material warm enough so that it will flow readily the exhaust pipe 80 of the cylinder 16 is directed through a valve 81 into a jacket 82 surrounding the supply pipe 30. The outlet 83 of this jacket is connected with a passage or chamber 84 which extends along the pipe 53 so as to heat the material just before it exudes from the nozzles. A by-pass 85 is provided with a valve 86 for cleaning out the pipe 30 with exhaust steam if desired. The pipe 53 has a clean out connection 87 from the pipe 14 and a clean out plug 88, so that it can be cleaned out by live steam.

From what has been stated it will be seen that an apparatus for this purpose constructed on the principles above illustrated, whether in the form shown or not, is a practicable and efficient machine for the purpose intended and that the steam employed for the pump is economically used as the exhaust thereof is employed for keeping the oil in a condition for flowing readily through the pipes and nozzles. It will be seen, also, that the device is designed for the purpose of securing a high efficiency in the operation thereof and in the employment of the labor of the gang of men who work with it. It

will be seen also that for the operation of the machine itself, only the men are required who operate the road roller and one other to stand on the vehicle D, steer it, and control the nozzles F.

It will be observed that a feature of importance lies in the provision of mechanism whereby an attendant, standing on the frame or draft tongue of the trailer, may steer the trailer independently of the preceding vehicles, whereby this attendant will have entire control over the trailer independently of the attendant who is controlling the steam roller, so that the attendant on the trailer can so guide the trailer that the material may be deposited close up to a track rail or to the adjacent edge of a previously coated portion of the road-way. This is a very important function in that it avoids spreading the material on railway tracks and also prevents overlapping upon previously coated surfaces. It is important that this control of the trailer shall be exercisable at a point on the trailer, where the attendant may maintain a careful watch upon the material as it issues from the nozzles. It will be observed also that a feature of importance in this machine lies in the fact that the tank vehicle may be readily disconnected from the train of vehicles without disrupting the steam connection between the steam engine on the roller and the steam engine on the trailer, whereby it is possible with our apparatus to employ several tank wagons and thus keep the apparatus fully supplied with the surfacing material. It is essential that the surfacing material shall be previously heated to a liquid state. This heating process requires considerable time and often has to be done at a distance of several miles from the place of application. In such cases it will be observed that the work is much expedited and important economies effected by having several tank wagons so that while one is being emptied on the road bed the others may be in the act of loading or heating or in transit. In this way our apparatus may be kept practically in constant use so that the force of men accompanying the apparatus shall be kept busy practically all the time.

While we have illustrated and described a preferred embodiment of the invention, we are aware that it can be carried out in many other ways than that illustrated. Therefore, we do not wish to limit ourselves to the specific form shown, but

What we do claim is:—

1. In an apparatus for surfacing roads and the like, the combination with a tank, pipe fittings connected with said tank at the rear thereof through which the material of the tank may be discharged comprising a Y having a central straight branch, a vehicle at the rear of the tank having a tongue, and

means for removably connecting said tongue with the straight branch of said Y, whereby the said vehicle will be drawn along centrally with the tank.

2. In an apparatus for surfacing roads and the like, the combination with a tank, pipe fittings connected with said tank at the rear thereof and extending downwardly therefrom through which the material of the tank may be discharged, a vehicle at the rear of the tank, nozzles thereon, means for removably connecting said rear vehicle with said pipe fittings whereby said vehicle will be drawn along centrally with the tank, and means carried by said rear vehicle connected with said fittings for drawing the material from the tank and supplying it to the nozzle.

3. In a device for surfacing roads and the like, the combination of a distributing pipe having nozzles thereon and made in sections adapted to be closed from each other, a pipe for receiving molten material under pressure, a connection between said pipe and each of said sections, a valve in each connection, and means for simultaneously operating said valves.

4. In a device for surfacing roads and the like, the combination of a distributing pipe having nozzles thereon and made in sections adapted to be closed from each other, a pipe for receiving molten material, a connection between said pipe and each of said sections, a valve in each connection, an operating lever, and means for connecting each of said valves with the lever.

5. In a device for surfacing roads and the like, the combination of a distributing pipe having nozzles thereon and made in a plurality of sections adapted to be separated from each other, a connection for introducing molten material into each of said sections, a valve for each of said connections, an arm on each of said valves for operating it, a pivoted operating lever, a link connected with each of said arms each having a hook, and pins on the operating lever adapted to be engaged by said hooks, whereby any of said valves can be disconnected from the operating lever by turning the links out of engagement with the pins.

6. In an apparatus for spreading heated liquid material upon road-ways, the combination of a steam road roller, a tank vehicle detachably hitched thereto, a trailer vehicle detachably hitched to the tank vehicle and carrying means for forcibly ejecting and spreading surface material, said means having detachable connection with the supply of material in the tank, a steam engine on the trailer for operating said means, and a pipe for supplying steam to said engine extending from said engine past the tank vehicle and connected to the steam generator on the roller vehicle, said pipe being readily de-

tachable from the tank vehicle, whereby the tank vehicle may be disconnected from the roller and from the trailer without breaking the steam connection between the roller and the trailer and another similar tank vehicle substituted therefor.

In testimony whereof we have hereunto

set our hands, in the presence of two subscribing witnesses.
